MERRY-GO-ROUND

Filed June 8, 1922

2 Sheets-Sheet 2

William H. Weaser,
INVENTOR.

BY Oscar F. DeWitt.
ATTORNEYS.

UNITED STATES PATENT OFFICE.

WILLIAM H. WEASER, OF PITTSFIELD, MASSACHUSETTS.

MERRY-GO-ROUND.

Application filed June 8, 1922. Serial No. 566,793.

To all whom it may concern:

Be it known that I, WILLIAM H. WEASER, a citizen of the United States, residing at Pittsfield, in the county of Berkshire and 5 State of Massachusetts, have invented certain new and useful Improvements in Merry-Go-Rounds, of which the following is a specification, reference being had therein to the accompanying drawings.

10 My invention relates to an improved merry-go-round, which is especially, but not necessarily, designed for use of children, the same being such in construction that it is manually operated by one occupant either 15 by a hand rope or lever arranged in convenient reach of the operator.

The principal object of the invention is to generally improve devices of this class by providing one of extreme simplicity and 20 durability which is well balanced and so constructed that it is very easy for a single child to propel the same.

Another object of the invention is to provide a pleasure device of this class which 25 embodies a novel arrangement of parts for imparting a rather speedy rotation to the seat carrier without requiring the operator to exert himself to such a degree as to become readily tired.

30 Another object is to produce a merry-go-round of this class that is well balanced, of durable construction, inexpensive and so constructed that it can be easily taken apart and repairs made.

35 With these and other objects in view, as hereinafter appear, the invention consists in certain novel and peculiar features of construction and organization as hereinafter described and claimed; and in order that 40 it may be fully understood reference is to be had to the accompanying drawings, in which: Figure 1 is a plan view of the merry-go-round, in part section showing the details of construction more clearly in accordance 45 with my invention. Figure 2 is an elevation view, in part section showing the details of the construction more clearly. Figure 3 is a sectional view with parts in elevation showing in part the operating mechanism of 50 my invention. Figure 4 is a plan view showing in detail another means of operating my invention. Figure 5 is an elevation view of Figure 4 showing in detail the means of operating my device.

55 Referring to the drawings, the numeral 1 designates a base from which a standard

rises, this standard being formed of a hollow tubular member 2 and provided with a journal or seat 3 removably arranged. The standard is provided with a slot on each side 60 into which sets the two pins 4. The pins are for the purpose of rendering the journal stationary on the standard. In the standard is a shaft 5 which extends above the upper end of the standard and through the journal 3 and is securely and permanently secured to the spider 6. A ratchet 7 is keyed or otherwise permanently affixed to the journal 3. By carefully examining the sectional view appearing in Figure 3 it will 70 be seen that the lower end of the shaft 5 and the upper end of the shaft and the spider 6 are specially constructed to accommodate ball bearings 8 interposed between the shaft and the standard, and the ratchet and the spider 6 constituting a part of the seat carrier. The shaft 5 is provided with a journal 43 which fits snugly within the standard and serves as a brace to take up any play or 75 loose motion that otherwise may be imparted to the shaft.

The spider 6 is mounted on the shaft and is held in place by the radial bars 9. With this arrangement, it will be seen that the entire carrier can be removed whenever necessary or desired. The carrier in addition to embodying this spider includes a plurality of radial seat supporting arms 9 which are secured by a thread or otherwise to the seat carrier and secured on the outer end by a 80 clamp 10. The clamp is secured permanently to the circular member 35 by means of a set screw or otherwise. It will be seen that by the removal of the clamp 10 that the radial arms 9 can be easily removed. The upper 85 end of the spider 6 is provided with an extension 11, this extension being securely and permanently fastened to the spider by a thread, or otherwise and provided on its upper end with a collar 12. As an additional 90 means of holding the seat carrier I employ a plurality of radial arms 13 which are secured to the collar 12 on the inner ends, and to the clamp 10 on the outer ends by means of a nut 14. It will be seen that by adjusting 95 the nut 14 that any play or loose motion in the seat carrier can be easily overcome. The merry-go-round proper is provided with a foot board 15 which is constructed of suitable material and open in the center. The 100 upper end of the merry-go-round is provided with a hollow circular tubular member 35,

2
preferably of steel tubing, and securely fastened and connected with the foot board by means of a plurality of vertical bars 17. The tubular member 35 is equipped with a coupling 36 which is secured to the tubular member by a set screw or otherwise. The coupling 36 is slidably arranged on the tubular member and can be moved along the tubular member to provide for the removal 5 of the clamps 10 which are also slidably arranged on the tubular member. The bars 17 are secured to the foot board at their lower end and are so designed to pass through the seats 18 on the outer side and securely 10 and permanently fastened to the clamp 10 on their upper end, thus forming a rigid construction to the merry-go-round. A substantially shaped arm 19 is mounted on the journal 3 between the upper end of the standard 15 and the ratchet 7 and is free to rotate about the journal 3. This arm serves to carry a pawl 20 which is designed for co-operation with the teeth of the ratchet. A plurality of seats 18 are supported by the vertical bars 17 and the foot board 15 and at least one of these seats is designed to be occupied by the operator, that is the person who constitutes the power for manually actuating the device. Of course if found advisable, one or more of the remaining seats could be of course equipped with the operating means to enable the work to operate the device to be equally divided among the several occupants.

35 For the sake of clearness, a part only of the radial bars 9 and 13 are shown in Figures 1 and 2, and only a single operating structure has been shown. The pawl 20, it will be seen, is secured to the arm 19 by means of a pin 21. The pawl is held in contact with the ratchet 7 by means of a torsion spring 22 which is permanently fastened to the pawl on its one end and to the arm 19 on its other end. A sprocket or pulley 23 is fastened to the arm 45 by a pin 24 and said sprocket or pulley is free to rotate about the pin 24. A flexible wire or chain 25 is secured on its one end to the operating lever 26 and is placed around the sprocket or pulley and secured at its other end by means of a clamp 27 which is permanently secured to one of the radial bars 9 to render it secure about the pulley or sprocket. A torsion spring 28 is permanently secured on its one end to the outer end 50 of the arm 19 and on its other end to the clamp 27. The operating lever 26 is secured to the radial bar 9 by means of two braces 29 and held in a position parallel to the radial bar 9. The braces 29 are provided with a slot 30, and the operating lever 26 sets in the slots provided for this purpose in the braces and is firmly held in place by the clamps 31 but free to rotate about in the slots. By referring to the drawings, it will be seen 55 that the operating means comprises a lever

26 which is pivoted intermediate by the braces 29 and is equipped with a lever 32 which is permanently secured at the upper end by means of a set screw or otherwise to render it stationary with the lever 26, and at the lower end is equipped with a horizontal handle 33 designed to be grasped by the operator. The handle 33 is designed that it is free to rotate in the lower end of the lever 32 and can be moved either one side or the other so as not to interfere with the operator when getting in or out of the seat 18. It will be found convenient to operate by means of a rope in some instances and to permit this end to be accomplished I employ an extension to the lever 26, the outer end provided with an eye in which the rope 34 may be inserted if desired. The lever 32 may be such that it can be swung out of the way of the operator when the rope is used, any suitable construction being employed for enabling this result to be obtained.

By referring to the drawings, Figure 4 and Figure 5 show in detail another means which I employ to operate my device.

The arm 37 is designed to rotate about the standard 2 and is connected to a lever 26 by means of a flexible wire or chain 38. A pawl 39 is mounted on the arm 37 and is pivotally secured thereto by a pin 40, the pawl is held in contact with the ratchet 7 by means of a spring 41 which spring is permanently secured to the arm 37. The outer end of the lever 26 is equipped with a torsion spring 42, said spring securely and permanently fastened at its one end to the radial bar 9 and at its other end to the lever 26. It will be seen that a downward pull by the operator on the rope 34 will impart motion to the lever 26 and in turn to the arm 37 which will cause the parts to be momentarily locked and act as a unit to exert a thrust or push against the ratchet 7. On releasing the rope 34 the torsion spring 42 will cause the parts to return to their original position to allow the operator to exert another pull on the rope. It will be seen that the lever 32 can also be used to operate the device if found necessary or convenient.

Having thus described my invention the operation is as follows:

Assuming that the operator is in the seat on which the operating means is arranged and further assuming that the parts are in the position shown in the drawings, it will be seen that when the operator grasps the handle 33 and exerts a pull towards himself a motion will be imparted to the lever 32 and 26 which will be in turn exerted on the arm 19 and they will be momentarily locked and act as a unit to exert a thrust or push against the ratchet, inasmuch as the last named element is fixed, it is obvious that the rotary head or carrier will be

moved in a direction contrary to the pull exerted by the operator. During the motion the pawl will ride over the ratchet teeth and the operating means connected with the journal. It will be moved around the latter so that when the operator desires to obtain another pull, this can be done because the parts are in a convenient position to permit it. The operation will be exactly the same if the pull rope is used. It will be seen that the means of operating the device are the same when the device is constructed in accordance with the drawings as shown in Figure 4 and Figure 5. By carefully considering the description in connection with the drawings, persons familiar with devices of this class will doubtless be able to obtain a clear understanding of the invention, therefore, a more lengthy and detailed description is deemed unnecessary.

From the above description it will be apparent that I have produced a merry-go-round possessing the features of advantage enumerated as desirable, and I wish it to be understood that while I have shown and described what appears to be the preferred embodiment of the invention, I reserve the right to make all changes falling within the spirit and scope of the appended claims.

Having thus described my invention what I claim as new and desire to secure by Letters Patent is:—

1. An apparatus of the class described comprising a base, a tubular standard rising from the said base, a journal fixedly secured to the top of the said tubular standard, a carrier rotationally mounted on the top of the journal and a shaft depending from said carrier into the said tubular standard, ball bearings interposed between the shaft and the tubular standard, the shaft and the carrier and the shaft and the journal, a standard rising from the said carrier and a collar mounted thereon, a tubular circular member, clamps rigidly affixed thereto, radial bars depending from said collar and radial horizontal bars extending from the carrier to the said clamps, a circular foot board and seats arranged thereon, vertical side bars depending from said clamps and supporting said foot board, a fixed ratchet with respect to the carrying device, a pawl held in position by a spring to cooperate with said ratchet and movable about the latter, a carrying member for said pawl, said carrying member having a pulley rotationally connected thereto and a flexible wire passing around the said pulley, clamps and a spring on one of the horizontal radial bars, an operating lever pivoted on one of the horizontal radial bars by means of said clamps and held in position by means of said spring, said operating lever having an extension on the outer end which is provided with an eye to insert a pull rope to actuate the device, an actuating lever depending from the said operating lever and equipped with a handle to be used to actuate the device in place of the pull rope.

2. An apparatus of the class described, comprising a base, a tubular standard rising from the base and provided with slots at the top, a journal fixedly secured to the top of the said tubular standard and held in place by means of pins extending from the journal and engaging in the slots, a carrier rotationally mounted on the top of the journal, a shaft depending from the said carrier and removably fitted in the tubular standard, ball bearings removably interposed between the shaft and the tubular standard, the shaft and the carrier and the shaft and the journal, a standard rising from the said carrier and a collar mounted thereon, a tubular circular member, clamps rigidly affixed thereto, radial bars depending from said collar and radial horizontal bars extending from the carrier to said clamps, a circular foot board provided with an opening in the center and seats arranged thereon, vertical side bars depending from said clamps and supporting said foot board, a fixed ratchet with respect to the carrying device, a pawl held in position by a spring to cooperate with said ratchet and movable about the latter, a carrying member for said pawl, said carrying member having a pulley rotationally connected thereto and a flexible wire passing around the said pulley, clamps and a spring on one of the horizontal radial bars, an operating lever pivoted on one of the horizontal radial bars by means of said clamps and held in position by means of said spring, said operating lever having an extension on the outer end which is provided with an eye to insert a pull rope to actuate the device, an actuating lever depending from the said operating lever and equipped with a handle to be used to actuate the device in place of the pull rope.

2. An apparatus of the class described, comprising a base, a tubular standard rising from the base and provided with slots at the top, a journal fixedly secured to the top of the said tubular standard and held in place by means of pins extending from the journal and engaging in the slots, a carrier rotationally mounted on the top of the journal, a shaft depending from the said carrier and removably fitted in the tubular standard, ball bearings removably interposed between the shaft and the tubular standard, the shaft and the carrier and the shaft and the journal, a standard rising from the said carrier and a collar mounted thereon, a tubular circular member, clamps rigidly affixed thereto, radial bars depending from said collar and radial horizontal bars extending from the carrier to said clamps, a circular foot board provided with an opening in the center and seats arranged thereon, vertical side bars depending from said clamps and supporting said foot board, a fixed ratchet with respect to the carrying device, a pawl held in position by a spring to cooperate with said ratchet and movable about the latter, a carrying member for said pawl, said carrying member having a pulley rotationally connected thereto and a flexible wire passing around the said pulley, clamps and a spring on one of the horizontal radial bars, an operating lever pivoted on one of the horizontal radial bars by means of said clamps and held in position by means of said spring, said operating lever having an extension on the outer end which is provided with an eye to insert a pull rope to actuate the device, an actuating lever depending from the said operating lever and equipped with a handle to be used to actuate the device.

In testimony whereof I set my hand and signature.

WILLIAM H. WEASER.
